REFRIGERATOR

Peter Köhler, Stockholm, Sweden, assignor, by
mesne assignments, to Servel, Inc., Dover, Del.,
a corporation of Delaware

Application May 3, 1932, Serial No. 608,888
In Germany July 30, 1931

13 Claims. (Cl. 62—170)

This invention relates to refrigeration and more particularly to a method and apparatus for quickly producing refrigeration to meet occasional extraordinary demands.

5 In small households it is often found uneconomical to keep a mechanical refrigerator in continuous operation, especially during the colder months of the year. When a refrigerator of the type usually provided for households has been shut down, a comparatively long time is required after resumption of operation to produce the desired amount of refrigeration and when it is desired to make ice cubes or cool bottles, or the like, considerable delay is experienced.

15 Guests in hotels often desire ice or cool drinking water on very short notice but storage space for foodstuffs is not required.

20 In accordance with this invention, a refrigerator is provided by means of which the above problem is satisfactorily and inexpensively solved. There is contemplated a refrigerator having a cooling element adapted to receive various objects to be cooled including bottles, ice cube trays, and the like, and which may be operated by water from the city mains or local supply and in which refrigeration is produced immediately the water is turned on.

25 Further objects and advantages will be apparent from the following description taken in connection with the accompanying drawing, in which,

30 Fig. 1 shows schematically an apparatus for carrying out the method of refrigeration contemplated by this invention;

35 Fig. 2 is a modification of the apparatus shown in Fig. 1; and

Fig. 3 is a modification of the apparatus shown in Fig. 2.

40 Referring to Fig. 1 of the drawing, a container 10 is provided with a capped filling opening 11 through which a quantity of cooling liquid is introduced into the container, such liquid having suitable evaporating and condensing tem-

45 peratures with pressure differences which can be produced by forces available in the household, such as water pressure. Dichlormethane has been found to be particularly suitable for use in this type of refrigerator. A conduit 12 connects

50 the top of the container 10 with the top of a similar container 10a. Injectors 13 and 13a are disposed in conduit 12, the injector 13 being directed into container 10 and the injector 13a being directed into container 10a. These in-

55 jectors are connected respectively through con-

duits 14 and 14a to a fluid supply such as a water pipe 15 and are selectively controlled by a two-way shut off valve 16.

The container 10 is provided with an overflow conduit 17 which discharges above the container, 5 as shown, and is provided with a check valve 18 operated by pressure outwardly from the container. The symmetrical container 10a is likewise provided with a conduit 17a having a check valve 18a. In the containers are similar vertical pipes 19 and 19a which extend from the bottom of the containers to a point above the liquid levels regulated by the valves 18 and 18a, as hereinafter described.

In operation, if control valve 16 is turned so 15 that water is discharged through the injector 13a into the container 10a, the pressure is reduced above the dichlormethane in container 10 and the pressure is increased in container 10a. Due to the decrease in pressure in container 10, 20 the dichlormethane evaporates, the heat of evaporation being supplied by the liquid which can then be used for cooling. The dichlormethane vapor is drawn through conduit 12 and injected with the water into container 10a in which, due 25 to the increased pressure and the cooling effect of the water, the vapor condenses to a liquid. Since dichlormethane does not mix with water but stratifies, the condensate will collect in the bottom of the container 10a with the water on 30 top. The conduit 17a is connected to the container 10a at a level above that which would be attained if all of the dichlormethane were in this container. The valve 18a is adjusted so that it opens at a certain pressure in the 35 container 10a, allowing the water to discharge through conduit 17a over the container, thus obtaining a further cooling effect. This effect could be increased, if desired, by providing around the container 10a a jacket provided with 40 an overflow for retaining the water discharged from conduit 17a or the container could be covered by a porous material which absorbs the discharged water.

If all of the dichlormethane has been evaporated from container 10 and condensed in container 10a, the valve 16 can be turned to direct water through the injector 13 into container 10. Obviously the valve 16 may be made automatic by the use of a thermostat, as well known in 50 the art. The process just described now takes place in the opposite direction, the pressure being decreased in container 10a and increased in container 10. The conduit 19a is provided to insure evaporation of the dichlormethane which 55

is covered by a layer of water in the container 10a. This conduit 19a, and the same is true of conduit 19 in the reverse process, functions as a thermosiphon from which any water is ejected 5 by ascending gas bubbles thus affording direct communication from the cooling liquid to the gas space in the container. In practice, the pipes 19 and 19a are preferably arranged outside of the containers in order to prevent possible freezing 10 of the water. The presence of a certain amount of water above the cooling liquid in the container functioning as an evaporator is advantageous as it lowers the vapor pressure, thus affording lower temperatures and more rapid 15 refrigeration. Also, some of the water will evaporate.

In a simplified device as just described in connection with Fig. 1, it is difficult to obtain a complete separation of the dichlormethane from 20 the water and a small amount will be carried away with the water discharged through conduits 17 and 17a, which amount, after some time, would have to be replaced. However, apparatus of this nature may be arranged to 25 obtain substantially complete separation of the cooling liquid and water. Such arrangements are shown in Figs. 2 and 3 in which only half of the apparatus is shown since the other half is identical as in Fig. 1.

30 Referring to Fig. 2 the container 10 described in connection with Fig. 1 is replaced by a condenser 20 and an evaporator 21. The injector 13 discharges into one end of the condenser 20 which communicates at its other end with the 35 upper portion of the evaporator 21. The condenser is provided with a plurality of baffle plates 22 having staggered apertures 23 along the top and smaller staggered apertures 24 along the bottom. From several points along the bottom of the condenser, conduits 25 connect to conduit 26 which discharges into the evaporator 21. From the upper part of the evaporator 21 leads a conduit 27 provided with an adjustable 40 pressure operated check valve 28, the conduit 27 discharging over the condenser 20 which, if desired, may be provided with some form of cooling jacket as suggested in connection with Fig. 1. A conduit 29 extends from the bottom of the evaporator 21 upwardly to a point above 45 the liquid level in the condenser 20 as determined by the adjustment of valve 28.

The operation of the apparatus just described in connection with Fig. 2 is identical with that described in connection with Fig. 1 except that, 50 due to the baffle plates 22 in the condenser 20, a greater stratification of the dichlormethane and water takes place before reaching the outlet valve 28. The baffles 22 function to decrease turbulence in the condenser 20 whereby the dichlormethane sinks to the bottom and flows to the evaporator through the several conduits 55 and conduit 26. As shown, the evaporator 21 is adapted to receive trays of water for making ice cubes but this is merely suggestive and the evaporator may be constructed in any manner desired to accommodate bottles or any other objects to be cooled, depending upon the service required.

In Fig. 2 the condenser and evaporator are 60 shown on the same side of the injector 13 but a still greater separation of water and dichlormethane may be obtained by employing an arrangement illustrated in Fig. 3 in which the evaporator and condenser are located on opposite sides of the injector. In this arrangement,

the injected water and entrained vapor enter the condenser 30 by overflow through aperture 35 from chamber 36. The condenser is provided with a plurality of baffles 32 and, at the end opposite the injector, is provided with the overflow conduit 37 controlled by check valve 38. As in the previous arrangement, the baffles 32 are provided along the top with openings 33 which, however, diminish in size in the direction from the aperture 35 to the overflow conduit 37. 10 along the bottom, the baffles 32 are also provided with openings 34 which increase in size in the direction from the overflow conduit 37 to the evaporator 21.

When water is discharged through the injector 15 13, water and dichlormethane vapor drawn through conduit 12, as previously described, enter chamber 36 from which the water overflows through aperture 35, filling first the evaporator 31 and then the condenser 30, while the dichlormethane condenses in condenser 30. The condensate collects at the bottom of the condenser 30 and flows through the openings 34 in the baffles 32 into the evaporator 31 where it sinks to the bottom, being heavier than the water, displacing the latter. The flow of water toward the overflow conduit 37 is through the gradually reduced openings 33 in the baffle plates 32 whereby turbulence is gradually damped, thereby allowing the condensed dichlormethane to more 30 readily sink to the bottom. Obviously the size of the openings 33 should never be less than the nozzle opening, for this would again produce turbulence.

It will be obvious to those skilled in the art 35 that various other changes may be made in the construction and arrangement without departing from the spirit of the invention and therefore the invention is not limited to what is described in the specification and shown in the drawing 40 but only as indicated in the following claims.

I claim:

1. The process of refrigeration which comprises applying a jet of water to aspirate vapor from above a body of cooling liquid immiscible 45 with water, condensing the vapor by the pressure of and heat transfer to the water, separating the condensate from the water and removing the water, against a gas pressure, from the presence of the separated condensate, by developing a pressure above a predetermined value on the condensate and water.

2. The process of refrigeration which comprises applying a jet of water to aspirate vapor from above a body of cooling liquid immiscible 55 with water, condensing the vapor by the pressure of and heat transfer to the water, separating the condensate from the water, removing the water above a predetermined quantity, and utilizing the water thus removed for further 60 cooling the vapor.

3. The process of refrigeration which comprises utilizing a jet of water to aspirate vapor from above a body of dichlormethane, condensing the vapor by the pressure of and heat 65 transfer to the water, separating the water and condensate by stratification, and removing the water from above the condensate by developing a pressure above a predetermined value.

4. Refrigerating apparatus comprising two 70 closed containers, a conduit between the upper portions of said containers, two injectors in said conduit each connected to discharge into one of said containers, a valve connected to selectively control a supply of fluid under pres- 75

sure to said injectors, an overflow conduit from each of said containers, a check valve in each overflow conduit, and a conduit from the bottom of each container opening into the upper part thereof.

5. Refrigerating apparatus comprising two closed containers, a conduit between said containers, and means associated with said conduit for selectively directing a jet of water to create 10 a pressure difference in either direction between said containers.

6. An evaporator comprising a container for cooling liquid having an outlet conduit, a fluid jet aspirator in said conduit, and a narrow conduit 15 from the lower part of said container opening in the upper part of the container above the normal liquid level therein.

7. A condenser-evaporator comprising a closed container, means for injecting water and vapor 20 into said container, and means for withdrawing vapor from said container, said means being selectively operable.

8. A condenser-evaporator comprising a closed container having a conduit connected to the upper part thereof, a water jet for ejecting vapor through said conduit into the container, a water jet for aspirated vapor from said container, said jets being selectively operable, an overflow conduit from said container having a pressure 30 responsive valve and a narrow conduit from the lower part of said container opening into the upper part above the normal liquid level therein.

9. Refrigerating apparatus including a condenser-evaporator comprising a closed container having an overflow conduit controlled by a pressure responsive check valve and a narrow conduit from the lower part to the upper part of the container; a second similar condenser-evaporator, a conduit connecting said condenser-evaporators, two water jets in said conduit each 40 directed to discharge into one of said condenser-evaporators, and means for selectively supplying water under pressure to said jets.

45. 10. In refrigerating apparatus of the class described a condenser-evaporator comprising a horizontally elongated container having a well portion at one end thereof, a conduit connected to the other end of said container, selectively operable means associated with said conduit for injecting water and vapor into said container and aspirating vapor therefrom, a plurality of baffles in said container between said conduit and said well portion, an overflow conduit having 50 a check valve from the upper part of said well

portion, and a narrow conduit from the bottom of said well portion to the upper part of said container, opening above the normal liquid level therein.

11. In refrigerating apparatus of the class described, a condenser-evaporator comprising a horizontally elongated container having a well portion at one end recessed for the reception of material to be cooled, a conduit connected to the other end of said container, selectively operable means associated with said conduit for injecting water and vapor into said container and aspirating vapor therefrom, a plurality of baffles in said container between said conduit and said well portion, a manifold connecting a plurality of points in the bottom of the baffle section of the container directly to said well portion, an overflow conduit from the upper part of said well portion, an adjustable pressure responsive check valve in last said conduit, and a narrow pipe 20 from the bottom of said well portion to the upper part of said container, opening above the normal liquid level therein. 5

12. In refrigerating apparatus of the class described a condenser-evaporator comprising a horizontally elongated container having a well portion at one end, an overflow conduit from the other end of said container having a pressure operated check valve, a chamber within said container intermediate the ends thereof having an opening in its upper portion, a conduit communicating with said chamber, selectively operable means associated with the last said conduit for injecting water and vapor into said chamber and aspirating vapor therefrom, and baffles in said container between said chamber and said overflow conduit. 25 30 35

13. In refrigerating apparatus of the class described a condenser-evaporator comprising a horizontally elongated container having a well portion at one end recessed for the reception of material to be cooled, an overflow conduit from the other end of said container having a pressure operated check valve, a chamber within said container intermediate the ends thereof having an opening in its upper portion, a conduit communicating with said chamber, selectively operable means associated with the last said conduit for injecting water and vapor into said chamber and aspirating vapor therefrom, and partitions in said container between said chamber and said overflow provided with apertures at the top and bottom decreasing in size in the direction away from said chamber. 40 45 50
